(57) **CLAIM**

The ornamental design for a headboard, as shown and described.

DESCRIPTION

FIG. 1 is a perspective view of a headboard showing my new design;

FIG. 2 is another perspective view thereof;

FIG. 3 is a front elevation view thereof;

FIG. 4 is a back elevation view thereof wherein the heavier dotted line represents the cross-sectional view of FIG. 9.

FIG. 5 is a top plan view thereof;

FIG. 6 is a bottom plan view thereof;

FIG. 7 is a right view thereof;

FIG. 8 is a left view thereof; and,

FIG. 9 is a right cross-sectional view taken from the heavier dotted line of FIG. 4, wherein the diagonal shading represents cross-sectional area.

The broken lines illustrate portions of the headboard that form no part of the claimed design.
